UNITED STATES PATENT OFFICE.

MICHAEL CONROY, OF IONIA, MICHIGAN, ASSIGNOR OF ONE-HALF TO GEORGE S. HARGER, OF SHERIDAN, MICHIGAN.

CONCRETE-MIXER.

1,003,400.

Specification of Letters Patent. Patented Sept. 12, 1911.

Application filed April 20, 1908. Serial No. 428,160.

To all whom it may concern:

Be it known that I, MICHAEL CONROY, a citizen of the United States of America, residing at Ionia, in the county of Ionia and State of Michigan, have invented certain new and useful Improvements in Concrete-Mixers; and I do hereby declare the following to be a full, clear, and exact description of the invention, such as will enable others skilled in the art to which it appertains to make and use the same.

My invention relates to improvements in mortar mixers, and its object is to provide a simple easily operated device, and to provide the same with various new and useful features hereinafter more fully described and particularly pointed out in the claims.

My device consists essentially of a dry mixer, a funnel below the dry mixer to receive the mixed material; means for supplying water to the surface of the funnel to moisten the dry material; a conveyer below the funnel and adapted to further mix the material and discharge the same from the machine, and means for transmitting motion to the various parts, as will more fully appear by reference to the accompanying drawings in which:

Figure 1, is a side elevation of a device embodying my invention; Fig. 2. a vertical section of the same on the line 2—2 of Fig. 1.; and, Fig. 3 a sectional detail at right-angles to Fig. 2.

Like numbers refer to like parts in all of the figures.

1 represents a hopper to receive the sand and 2 a similar hopper to receive the cement, said hoppers being separated by a vertical partition, at the respective sides of which are the rotary feed regulators 8^a and 9^a mounted on shafts 8 and 9 partially inclosed at their outer sides by concave extensions of the respective hoppers whereby material is directed into the downwardly turning sides of the regulators only, thus aiding in rotating the same.

5 is a driving shaft mounted above the partition between the hoppers and spaced apart therefrom, on which shaft are mounted radial slotted arms 6 adjustably supporting buckets 7 into which the sand is discharged from a spout 3 located at an elevation above the sand hopper and adjusted to direct the sand into the descending buckets.

This device thus serves as a driving wheel 5 operated by the weight of the sand as it is discharged from the spout 3. The sand is discharged from these buckets into the hopper and thence into the downwardly turning side of the feed regulator 8. A spout 4 is provided by which the cement is supplied to the hopper 2, which cement is directed between the side of the hopper and the ascending buckets 7 and discharged into the downwardly turning side of the feed regulator 9. The sand and cement after thus furnishing motive power to operate the machine are discharged from these feed regulators through a single opening 2^a below the regulators. If found necessary the spouts 3 and 4 may be extended upward and the sand and cement thus given increased momentum to increase the power delivered thereby. 25 is a truncated conical shield below this discharge opening through which extends a vertical shaft 23 journaled at its upper end in the partition between the hoppers and also journaled in a bearing beneath the shield 25. A shaft 10 extends horizontally from near the shaft 23 outward and is connected to the shaft 23 by bevel gears 10^a to rotate said shaft. Concentric with this shaft 23 is a tube or drum 26 supported thereby and connected thereto by radial arms 27, a portion only of which are shown. 35 These arms serve also as beaters to effectually mix the material passing downward through the tube. Beneath the tube 26 is a funnel 28 into which the mixed dry material is discharged. Above the rim of this funnel and adapted to discharge numerous fine streams of water upon the inside surface of the funnel is a hollow ring 29 connected by a pipe 30 to any suitable water supply. Beneath the funnel is a conveyer trough 31 95 extending outside the machine in which is a conveyer screw 11 to mix and remove the wet material from the machine.

To communicate motion from the driving shaft 5 to the shafts 8, 9, 10 and 11, I provide a sprocket wheel 12 on the driving shaft 5 connected by a chain 18 to a similar wheel 13 on the shaft 9, and connect the shaft 9 and the shaft 8 by a gear 21 and pinion 22, which gear and pinion I prefer 105 to make changeable to vary the relative speed of the feed regulators to adjust the proportion of sand and cement. The feed

regulators 9^a and 8^a may also differ in size for like purpose, if preferred, and this gear and pinion may be mounted on the other end of the regulator shafts instead of as shown to more conveniently change the same. To transmit motion from the shaft 9 to the shafts 10 and 11 a sprocket wheel 14 is mounted on the shaft 9 and connected by a chain 19 to a wheel 15 on the shaft 10 and the shafts 10 and 11 are connected by means of sprocket wheels 16 and 17 and a chain 20. Above the shield 25, I attach a sweep 24 to the shaft 23 to remove the material falling upon the closed top of the shield and push the same over the outer angle thereof. This material escaping from the shield, which is smaller in diameter than the interior of the tube 26, first impinges upon the inner surface of the tube 20 and thence rebounding inward is broken up, scattered and mixed by the revolving arms 27 as it passes downwardly, so that when it reaches the funnel 28, it is thoroughly commingled ready for mixing with the water discharged from the ring 29. This water flowing down over the inner surface of the funnel is quickly distributed and mingled with the material which escapes from the lower end of the tube 26. The centrifugal action of this dry mixer discharges this material from the lower end of the tube upon the upper part of the funnel, down which it flows together with the fine streams of water discharged from the ring 29 and thus reaches the conveyer very equally and accurately mingled with the water, requiring but

little further mixing to constitute properly mixed mortar for concrete work.

What I claim is:

1. A concrete mixer comprising a vertically disposed shaft, a tube surrounding the shaft, radial arms connecting the shaft and tube, a shield surrounding the shaft above said tube, a horizontally disposed shaft extending outward from beneath the shield, 40 gears beneath the shield connecting said shafts, a funnel below the tube and shaft, means for supplying a spray of water to the upper part of the funnel, a conveyer below the funnel and means for communicating 45 motion to the horizontal shaft and to the conveyer.

2. A concrete mixer, comprising a vertical shaft, a truncated conical shield having a flat top closure through which the shaft 55 extends, a sweep on the shaft traversing the said top; a tube surrounding the shaft and of greater diameter than the shield, arms connecting the tube and shaft, a funnel below the tube and shaft, means for supplying a spray of water to the funnel, a conveyer below the funnel, a horizontal shaft 60 extending beneath the shield, gears beneath the shield connecting the said shafts and means for rotating the shafts and conveyer. 65

In testimony whereof I affix my signature in presence of two witnesses.

MICHAEL CONROY.
